(57) **CLAIM**

We claim the ornamental design for a writing instrument grip, as shown and described.

DESCRIPTION

FIG. 1 is a front view of the writing instrument grip of the new design.

FIG. 2 is a back view thereof.

FIG. 3 is a side view of FIG. 1.

FIG. 4 is another side view thereof.

FIG. 5 is a top view of FIG. 1.

FIG. 6 is a bottom view thereof.

FIG. 7 is a bottom-side perspective view thereof; and,

FIG. 8 is a bottom-side perspective view of the writing instrument grip in use.

The broken lines in the figures are included to show portions of the writing instrument grip and the environment that form no part of the claimed design.

1 Claim, 5 Drawing Sheets---
